(57) **CLAIM**

The ornamental design for a re-locatable support surface for a media player, as shown and described.

DESCRIPTION

FIG. 1 is a perspective view of a re-locatable support surface for a media player showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines adjacent to the shade lines indicate the boundary of the claimed design. None of the broken lines form part of the claimed design.
